US0D1041914S

(12) **United States Design Patent** (10) **Patent No.:** **US D1,041,914 S**
(45) **Date of Patent:** ** *Sep. 17, 2024

(54) **SERVO AMPLIFIER**

(71) Applicant: **FANUC CORPORATION**, Yamanashi (JP)

(72) Inventor: **Kazuhiro Yamamoto**, Yamanashi (JP)

(73) Assignee: **FANUC CORPORATION**, Yamanashi (JP)

(*) Notice: This patent is subject to a terminal disclaimer.

(**) Term: **15 Years**

(21) Appl. No.: **29/836,216**

(22) Filed: **Apr. 25, 2022**

(30) **Foreign Application Priority Data**

Oct. 25, 2021 (JP) ..... 2021-023136 D

CLAIM

The ornamental design for a servo amplifier, as shown and described.

DESCRIPTION

FIG. 1 is a front-right side-top perspective view of a servo amplifier showing my new design;

FIG. 2 is a front-left side-top perspective view thereof;

FIG. 3 is a front-right side-bottom perspective view thereof;

FIG. 4 is a front-left side-bottom perspective view thereof;

FIG. 5 is a front view thereof;

FIG. 6 is a rear view thereof;

FIG. 7 is a top plan view thereof;

FIG. 8 is a bottom plan view thereof;

FIG. 9 is a right side view thereof; and,

FIG. 10 is a left side view thereof.

The broken line showing of the remainder of the servo amplifier represents portions which form no part of the claimed design.

1 Claim, 10 Drawing Sheets
